FILING CABINET, LOCK, AND TRAY

Stanley B. Freiberg, Cincinnati, Ohio

Original application February 25, 1929, Serial No. 342,645. Divided and this application March 17, 1930. Serial No. 436,366

4 Claims. (Cl. 45—2)

This is a divisional application of application Serial Number 342,645, filed February 25, 1929.

An object of the invention is to provide a filing cabinet of simple, sturdy construction, having a minimum of parts and having the parts so related that the cabinet can be expeditiously built up or assembled.

Another object is to provide a device of the character indicated, wherein a positive locking means may be readily incorporated, and which so cooperates with the cabinet and drawers received therein, that the control means of the lock is not subjected to strain or shock, all force tending to open locked trays or drawers being directed against the cabinet structure.

Another object is to provide a device of the character indicated in which a plurality of drawers or trays may be locked by a single locking member, parts of the cabinet being so formed as to provide an operating space for the locking member and at the same time being developed into cabinet reenforcing means as well as cooperating means of the shelf mounting structure.

These objects are attained by the means described herein and set forth in the accompanying drawings, in which:

Fig. 1 is a perspective view of a cabinet of the present invention with shelves and shelf-mounting appurtenances of the invention installed therein, parts being broken away.

Fig. 2 is a front elevational view of the cabinet.

Fig. 3 is a view taken on line 3—3 of Fig. 2.

Fig. 4 is an isometric view showing the development of a shelf-mounting member of this invention.

Fig. 5 is an end view of one of the shelf-mounting members.

With reference to the drawings; the cabinet 12 comprises the side walls 13 and 14, top 15, the raised bottom 16 and rear wall 17, the latter and the corners adjacent thereto being suitably strengthened as indicated in Fig. 3. The panels 18, 19 and 20 bordering the front of the cabinet are preferably formed by turning in portions of the sides and top respectively. After the formation of the panels 18 and 19, the vertical edge-ports of the cabinet sides are turned inwardly thereof to provide the vertical members or columns 21 and 22. Portions of column members 21 and 22 are formed to provide the opposed vertical channels 23 and 24 opening to the interior of the cabinet. Members 21 and 22 are spaced from the cabinet sides adjacent thereto whereby limited vertical passages 36 are formed. Members 21 and 22 are cut off immediately above the

raised bottom 16, which extends forwardly to abut the inner sides of panels 18 and 19, thus closing the channels 23 and 24 at the lower ends thereof. A base panel 25 extends between panels 18 and 19 the upper edge of panel 25 abutting bottom 16 as indicated at 26 (Fig. 1).

The mountings 27, of this invention are individual members resembling channel bars and extending longitudinally of the cabinet in abutment with the inner faces of side walls 13 and 14. 65 Mountings 27 are preferably formed of metal sheets or blanks 28 which are provided at each end with extensions 29, 30 and 31. Blank 28 is bent, as indicated by dotted lines in Fig. 4, so as to provide a shelf member comprising an upper 70 surface portion 32, an intermediate ledge 33 and bottom 34. Extensions 29 and 31 are now in spaced alignment and project as tongues from ledge 32 and bottom 34 respectively. The shaped projections 30 are bent inwardly of the mountings, so that the top edges of extensions 30 fall immediately beneath the end edges of ledges 32 and 33, and the bottom edge of extensions 30, 75 immediately above the end edge of bottom 34.

The shelves 35 are substantially flat sheets of 80 a width slightly less than the inside width of cabinet 12, and of proper length to permit their insertion between rear wall 17 and the innermost projections of portions 21 and 22. Each shelf 35 is adapted to be supported on each side by 85 one of the mountings 27.

The mountings and shelves are positioned within the cabinet by a building-up process. Initially, two of the mountings 27 are oppositely disposed along the walls 13 and 14, the bottoms 34 of the 90 mountings resting upon the raised bottom 16 of the cabinet, and the open sides of the mountings 27 against the inner faces of walls 13 and 14. In so positioning the mountings, the extensions 29 and 31 are inserted in the limited vertical passages 36 provided by the turned-in members 21 and 22, whereby lateral movement of the forward portion of mountings 27, is prevented. A similar structure, or other suitable means, may be 95 employed in the rear of the cabinet.

After the first pair of mountings 27 has been thus positioned, a shelf 35 is placed thereon, resting upon the upper ledges 32 of the oppositely disposed mountings. Thereafter, a second pair of 100 mountings is operatively disposed upon the positioned shelf, and a second shelf placed upon the second pair of mountings, and in similar fashion until the cabinet is complete. The turned-in extensions 30 prevent the ledge 32 and bottom 34 from bending inwardly of the mountings 27.

after pressure is exerted thereon. Moreover, the interfitting relation of ledges 32 and 33 with extension 20 prohibits any outward bending or sagging of front wall 37 of the mountings 27.

- 5 The vertical channels 23 and 24 are adapted to receive the main lock element of a cabinet locking means such as set forth in my co-pending application, Serial Number 342,645, filed February 25, 1929, the lock proper being adapted for positioning upon the panel 25, and the mechanism directly cooperating therewith being adapted for positioning within the space provided beneath the raised bottom 16 adjacent either the front, right or left hand corner of the cabinet, or both.
- 10 15 After the installation of the lock mechanism, the latter may be enclosed by suitable housing means attached to the bottom of the cabinet. The ledges 33 of the mounting members 27 are adapted to cooperate with tray guides such as that set forth in my co-pending divisional application, Serial Number 436,367, filed on even date herewith. Said guide on its forward portions is provided with a pair of laterally-projecting lugs adapted to ride upon the ledges 33 and to abut the turned-
- 20 25 30 35 35 in members 21 and 22 of the cabinet whereby the guide is retained in the cabinet. The guide, it might be further explained, is intended for cooperation with a tray or drawer such as shown in my co-pending application Serial Number 325,589, filed on December 11, 1928, which is adapted to be supported by shelves such as the shelves 35 shown in the present invention.

The cabinet of this invention can be manufactured with great economy due not only to the simplicity of its structural features but also to the fact that its interior constituent elements are formed entirely independent of the cabinet proper, while the time required for the assembling operation is almost negligible.

40 What is claimed is:

1. A filing cabinet comprising bottom, top, back and sides, a pair of upright channel members in the cabinet adjacent the front and spaced from the side walls thereof and providing a pair of opposed, vertical channels for receiving locking means and forming with the cabinet sides a pair of restricted, vertical passages, a plurality of bar-like members adapted to be positioned longitudinally of the interior of the cabinet against the sides thereof, an end of each bar being insertable within said restricted vertical passages whereby to limit lateral movement of the bar members, and a plurality of sheet members adapted each to be positioned upon and to have positioned thereon a pair of said bar members whereby through a building process, to provide the cabinet with a requisite number of spaced shelves.
- 45 50 55 60 65 70 75

2. The combination with a cabinet having lateral, turned-in border panels on its front, of a

pair of longitudinally-channelled column members extending vertically of the interior of the cabinet, each of said members being attached to one of said panels and in spaced relationship with the adjacent wall of the cabinet whereby to provide restricted vertical passages, the channels of said column members opening inwardly of the cabinet and being adapted to receive the lock bars of cabinet locking mechanism, and a plurality of bar-like members for supporting shelves within the cabinet, said bar-like members being adapted to extend longitudinally of the interior of the cabinet and having endwise extensions insertable in said restricted vertical passages for limiting lateral movement of the shelf-mounting members.

3. A reinforced shelf mounting member adapted to rest upon a shelf and to have a shelf superimposed thereon, said member comprising an elongated metal strip bent longitudinally to provide a shelf-supporting top portion, a relatively wide base spaced from and parallel with said top portion, a connecting wall between said two parts and bent to provide two vertical parallel sections joined by a horizontal section, and a shaped extension on said connecting wall at each end thereof, said extension being adapted to be turned inwardly of the mounting member into edgewise supporting contact against the inner faces of said top portion, base and horizontal section, the mounting member being adapted to be positioned with said connecting wall facing inwardly of the associated superimposed shelf for precluding bending of the member under the weight of the shelf.

4. The combination with a cabinet having a vertical channel at one end thereof, of a shelf mounting member adapted to rest upon a shelf and to have a shelf superimposed thereon, said member comprising an elongated metal strip bent longitudinally to provide a shelf-supporting top portion, a relatively wide base spaced from and parallel with said top portion, a connecting wall between said two parts and bent to provide two vertical parallel sections joined by a horizontal section, a shaped extension on said connecting wall at each end thereof, said extension being adapted to be turned inwardly of the mounting member into edgewise supporting contact against the inner faces of said top portion, base and horizontal section, and integral tongues on said top portion and base projecting beyond said extensions and adapted to be received in said vertical channel in positioning the mounting member, the latter at this time being turned with said connecting wall facing inwardly of the associated superimposed shelf for precluding bending of the member under the weight of the shelf.
